SOUND CONVEYING MEANS FOR PHONOGRAPHS

Filed Aug. 7, 1928

UNITED STATES PATENT OFFICE

HENRY O. DROTNING, OF NEW YORK, N. Y.

SOUND-CONVEYING MEANS FOR PHONOGRAFS

Application filed August 7, 1928. Serial No. 298,122.

My invention relates to sound conveying means for phonographs, radio receivers, and the like; and the same has for its object more particularly to provide a simple, efficient and compact device which may be manufactured and readily assembled at low cost, and which produces a tone of good quality.

Another object of the invention is to provide a device of the character specified in which the same is constructed to occupy a relatively constricted space such as in a portable set, without reduction in the tone quality or intensity of sound produced.

Further, said invention has for its object to provide a device of the character specified in which a partition in the cabinet or casing of the sound producing instrument serves to rigidly support the device and to form therewith the complete sound conveying channel incapable of developing undesirable vibration of the walls thereof.

Further, said invention has for its object to provide a device of the character specified in which the member forming the partial sound conveying channel has a varying cross-sectional area following approximately an exponential curve.

Further, said invention has for its object to provide a device of the character specified in which the member constituting the partial sound conveying channel is molded to a form following said exponential curve.

Other objects will in part be obvious and in part be pointed out hereinafter.

To the attainment of the aforesaid objects and ends my invention consists in the novel details of construction, and in the combination, connection and arrangement of parts hereinafter more fully described, and then pointed out in the claims.

In the accompanying drawing:

Fig. 1 is a plan showing one form of device constructed according to and embodying my said invention;

Fig. 2 is a section thereof on the line 2—2 at Fig. 1; and

Fig. 3 is a perspective thereof.

Referring to the drawing, I have illustrated the device embodying my invention as incorporated in a phonograph of the portable

type having a casing 10, cover 12, a horizontal partition or motor board 14, and a motor 16 secured below the latter for driving the rotatable record support 18. The usual tone arm 20 is pivoted in an opening 22 through the forward portion of the partition 14, and the latter at the rear thereof is provided with a relatively enlarged opening 24 through which the sound produced issues.

Communication is established between the opening 22 and the opening 24 by means of a sound conveying channel 26 located below the partition 14 and formed in part by the partition 14 and in part by the member 28 secured to the partition at the lower side thereof.

The member 28 is preferably composed of moldable material, such as fabric impregnated with a suitable plastic substance, which has qualities suitable for conducting sound without undesirable vibration of the walls thereof.

The member 28 is readily formed in a mold of predetermined contour, and consists of a channel formation open at the top as indicated 30, and gradually increasing in width and depth towards the enlarged end thereof, and the same has a flange portion 32 thereon extending about the opening 30. The flange portion 32 serves for securing the member 28 to the lower side of the partition 14 by suitable means, such as the screws or tacks 34 which are disposed uniformly along the member 28 to secure the same to the partition, the two parts forming a rigid structure reducing appreciably the undesirable vibration characteristic of the ordinary horn which is secured at one or two points only.

The smaller end portion 36 of the member 28 extends transversely at the rear of the motor 16 and merges with the longitudinal intermediate portion 38 thereof, the latter portion terminating in an enlarged flaring end portion 40 in front of the motor registering with the opening 24 in the partition 14. The several portions 36, 38, and 40 provide a substantially U-shaped member having a recess 42 in which the motor 16 is received.

The successive cross sectional areas of the member 28 as illustrated in Fig. 1 by the

broken lines AA, BB, CC, etc. preferably increase with the length according to an exponential law. The relative increase in area is uniformly distributed over the whole length of the member 28 from the opening 22 to the opening 24. The value of the exponent used should be such that the final cross section of the member 28 approximately corresponds with the actual cross sectional area of the opening 24 in the partition 14.

10 The lateral wall portions 44 of the member 28 preferably diverge upwardly, and the lateral portion 40 thereof provides for the expansion of the sound wave as the same approaches the outlet 24. The wall 46 and the wall 48 of the portion 40 curve rapidly upwardly for directing the sound wave towards the orifice 24.

15 The edge of the wall portion 46 comprises a downwardly inclined flange 50 serving together with the flange 32 to reinforce and stiffen the member 28.

20 By my invention I provide a sound conveyor occupying a small space and producing even better results than those obtained by the ordinary relatively larger horns used in the larger phonographs of the non-portable type.

25 The member 28 is readily fabricated, and secured to the motor board 14 through the flange 32 by means disposed along the flange so that the member is supported entirely by and rigidly anchored to the board 14 to form therewith a sound conducting passage having walls not liable to vibrate.

30 Further the shape of the member 28 is such as to provide ample length of passage for the sound while retaining ample room for receiving the motor 16.

35 It is to be noted that the member 28 is readily molded of a material having acoustical qualities suitable for horns, the mold being constructed to produce a member having a channel following an exponential law as above described. The material of the member 28, the mounting therefor and the shape thereof all cooperate to provide a sound conveying passage which emits a sound of good quality and relatively high intensity, even though the restricted space in which the member 28 is disposed necessitates economy in the length of the sound conveying passage.

40 I claim:

1. A casing, a partition therein having a tone arm opening through it, a relatively larger opening in the partition for the egress of sound, a channel member open at one side secured to one side of said partition and supported thereby within the casing and forming therewith a sound conveying passage increasing in size from said tone arm opening to said relatively larger opening, said member having laterally extending end portions providing a space therebetween adapted to receive a motor.

45 2. A casing, a partition therein having a

5 tone arm opening through it, a relatively larger opening in the partition for the egress of sound, a channel member open at one side secured to one side of said partition and supported thereby within the casing and forming therewith a sound conveying passage increasing exponentially in size from said tone arm opening to said relatively larger opening, said member having laterally extending end portions providing a space therebetween adapted to receive a motor.

10 3. The combination with a casing, and a partition therein having an opening therethrough for entry of sound, and a relatively enlarged opening therethrough in spaced relation to the first opening for the egress of the sound, of a channel member of increasing cross-sectional area open at one side secured to said partition, and forming therewith a sound conveying passage between said openings; the larger end of said member having an open portion substantially coextensive in area with the larger opening in said partition and registering therewith.

15 4. A device of the character described comprising a sound conveying member of increasing width and depth, terminating in a laterally extending enlarged end portion; said member being open at one side, and a flange extending along the edges of the opening therein for attachment of the member to the surface of a partition to form an enclosed sound conveying passage.

20 5. The combination with a casing, and a partition therein having a tone arm opening therethrough, and a relatively enlarged opening therethrough in spaced relation to the first opening, of a channel member of increasing cross-sectional area following an exponential law, open at the top, and a flange extending along the opening in said member; said member being secured by said flange to one side of said partition and rigidly supported thereby within the casing; and the end portions of said member providing a space therebetween for receiving a motor; and the exit end of said member forming an open enlarged portion substantially coextensive in area with said larger opening and registering therewith.

25 6. A casing, a partition therein having a tone arm opening through it, a relatively larger opening in the partition for the egress of sound, a channel member open at one side secured to one side of said partition and forming therewith a sound conveying passage having lateral arms one of which opens into the tone arm opening and the other of which opens into the larger opening.

30 7. The combination with a casing, and a partition therein having an opening therethrough for entry of sound, and a relatively enlarged opening therethrough in spaced relation to the first opening for the egress of the sound, of a channel member of increasing

ing cross-sectional area open at one side, a flange extending about the edge of the member for attaching it to said partition and forming therewith a sound conveying passage between said openings; the larger end of said member having an open portion substantially coextensive in area with the larger opening in said partition and registering therewith.

8. A device of the character described comprising a cabinet, a motor board positioned within said cabinet, said motor board adapted to form the upper portion of an air column horn.

9. A device of the character described comprising a cabinet, a motor board within said cabinet, and a trough-shaped member associated with said motor board and forming therewith a resonant air column.

In testimony whereof, I have signed my name hereto.

HENRY O. DROTNING.
